TRIGGERING CIRCUIT

John B. Atwood and Robert E. Schock, Riverhead,
N. Y., assignors to Radio Corporation of Amer-
ica, a corporation of Delaware

Application September 26, 1945, Serial No. 618,760

6 Claims. (Cl. 250—27)

1

This application discloses an improved translating circuit as used in frequency shift telegraphy systems such as, for example, disclosed in U. S. Application Serial #632,978, filed December 5, 1945. In these signalling systems intelligence is transmitted by shifting the frequency of carrier current from a first frequency representing space to a second frequency representing mark. The mark and space frequencies may be separated by several hundred cycles.

At the receiver a carrier current so shifted or keyed from mark to space frequency is amplified as desired, reduced in frequency if desired, and fed to a limiter, discriminator and detector arrangement to derive bi-directional current which reverses in polarity as the transmitted current shifts from mark to space frequency and vice versa.

This pulsating current is amplified and filtered to remove noise components and fed to a tripping or triggering circuit of the general nature disclosed in Finch U. S. Patent #1,844,950, dated February 16, 1932. A specific triggering circuit may be as illustrated and described in the said U. S. Application Serial #632,978, filed December 5, 1945. The triggering circuit comprises a pair of tubes with their anodes and control grids cross-coupled and arranged and operated so that if current is initiated in one tube it is cut off in the other tube and vice versa. Although two tubes are shown with individual evacuated envelopes therefor, it is obvious that these tubes can be replaced by a single tube wherein one evacuated envelope encloses both electrode structures. Double triggering circuits may be used or parallel triggering tubes may be used but for explanation of the present invention a single triggering tube arrangement will suffice.

The current is tripped from one tube to the other thereof and vice versa in accordance with the magnitude of the pulsating current supplied to the grid of one of the tubes. The triggering circuit squares off the wave form and limits the same to supply at its output potential the magnitude of which shifts sharply between two values in accordance with shifts from mark to space frequency and vice versa. The trigger circuit may indirectly control a tone keyer or printer. In the example given the trigger circuit operates a stop-start printer through additional circuits not shown. The stop-start printer has been arranged so that it is essential that a mark character be transmitted to the printer in the absence of keying on the transmitter. In the system as explained the signals received are to terminate on

2

"mark" and start on "space". The transmitter will stop on mark but the possibility exists that a burst of static will pass through the receiver and operate the trigger so that it flips to the space condition. This is undesired since the stop-start printer is arranged to end on a mark character and start on a space character. If this happens the printer mechanism will continuously rotate and may not start in synchronism when keying commences. Much the same thing may happen when the transmitter goes off the air.

The broad object of the present invention is to improve triggering circuits in this respect. This is done by providing means for restoring the triggering circuit to a condition of stability whereat it comes to rest in the mark position. The means for accomplishing this is so arranged that the action does not take place until the passing of a suitable time period which is long with respect to the characters being received. When this is so, the restoring means will not operate between signal characters.

The means for restoring the triggering circuit to a selected condition of stability includes an electron discharge device arranged and operated under certain conditions to set up on one of the tubes a biasing potential which trips the circuit into the condition of stability wanted.

A further object of the present invention is to enhance the tripping action of the triggering circuit to make the same rapid and positive under control of the voltage of varying magnitude representing the signals. This is accomplished by arranging the tube used for the restoring action described briefly above so that in the presence of keying voltages the same assists or expedites or enhances the tripping action.

In describing our invention in detail reference will be made to the attached drawings wherein Fig. 1 illustrates a trigger circuit including trigger circuit stability restoring means which insures flipping or triggering of the circuit to a particular condition of stability in the event the same is for some reason left in the other condition of stability.

Figs. 2, 3 and 4 are curves used to illustrate the operation of our improved system.

In the drawings, tubes 110 and 114 are the vacuum tubes of the triggering circuit. The current of varying magnitude (positive with respect to ground) derived from rectifying the keyed currents after passing the same through a discriminator and detector and amplifier and low pass filter (not disclosed herein) are applied between ground and the input contact 102. The keyed

signal of varying magnitude appears across the grid bias resistor 103 and on the grid of the cathode follower type amplifying and coupling vacuum tube 104, whose conductivity is controlled by the signal. Resistances 91 and 92 are a voltage divider used to supply a positive voltage on the grid of tube 104 such that its grid-to-cathode potential is near the center of its dynamic range. The net grid-to-cathode voltage will still be negative due to resistor 108. This increases the alternating current input voltage the tube 104 will handle.

The current through the tube 104 varies in accordance with the keyed input and the potential across the cathode follower resistor 108 varies in a corresponding manner. The potentials of varying magnitude at the high potential end of resistance 108 are applied to the control grid of the tube 110 of the triggering circuit and also by condenser 152 to the control grid of the restoring vacuum tube 150. The anode of tube 110 is coupled to the grid of tube 114 by resistance 117. The cathode of tube 114 is connected to ground by variable resistance 111. The anode of tube 114 is coupled to the control grid of tube 110 by resistor 119. The anodes of the tubes 110 and 114 are also coupled by anode impedances 121 and 121' to the positive terminal of a source of direct current potential. Tubes 110 and 114 are in the triggering circuit to be controlled and restored to a selected state or condition of stability. Output may be taken between the anode of either tube 110 or 114 and ground, for example, as shown by the leads including condenser 125 labeled "Output."

In the absence of keying the grid of tube 150 is maintained slightly positive by virtue of voltage supplied from the voltage divider resistances 155 and 156 through resistance 154 to the said grid. In this condition tube 150 will present a low impedance plate to cathode circuit. One plate to cathode external shunt circuit of tube 150 includes the resistance 123, which with resistances 117 and 121 form a potential divider across the direct current source.

In mark condition a positive pulse is applied at 102, appears across 108 and is applied to the grid of tube 110 so tube 110 is conductive and tube 114 is non-conductive. It should be kept in mind that the received signals are to terminate on mark and start on space. We will assume, however, that static or other disturbance has tripped the circuit so that tube 110 is cut off and tube 114 is conductive. Then there is a large potential drop across resistor 123, since tube 110 is cut off thus raising the potential at its plate which is applied to the voltage divider including resistors 117, 121 and 123, to produce the positive voltage required for the grid of tube 114. However, tube 150 has its output impedance across this resistor 123 and since its grid is made slightly positive by resistance 154, and potential divider resistances 155 and 156, in the absence of keying, tube 150 presents a low impedance. Current flows in tube 150 and resistances 117 and 121 and the potential on the grid of tube 114 is reduced by the low impedance path through tube 150 and the trigger circuit flips to its condition of stability at mark frequency, i. e., tube 114 is made non-conductive and tube 110 is conductive.

After keying signals have been applied for some time, tube 150 develops a negative bias about which the keying pulses are centered. When keying stops, the resulting action depends upon whether the keying stops on mark or space. If

the keying stops on mark, the grid of tube 150 will be slightly positive and in the normal condition, ready for keying to recommence. If the keying stops on space tube 150 becomes cut off due to the negative bias built up on its grid and held by the time constant circuit including condenser 152 and resistance 154. The time constant of this circuit is long relative to the keying speed. This bias will gradually leak off and the grid of tube 150 will become slightly positive, thereby conditioning tube 150 to restore the trigger circuit if it is not in the proper state of stability.

This tube 150 performs another function between the time the keying starts and cutoff bias is built up on its grid. It helps throw the trigger as controlled by "mark" and "space" voltages by the following action.

In the invention as described the first thing that happens when keying commences is appearance of a negative pulse representing "space" across resistor 108 which is coupled to the grid of tube 150 through condenser 152. This is of large enough amplitude to cut off tube 150. This in turn applies a positive pulse to the grid of tube 114 (the drop across resistance 123) which will help throw the trigger circuit. The negative applied pulse is also and simultaneously applied to the grid of tube 110, which is the normal way the trigger is tripped when tube 150 is finally cut off by the bias supplied by the keying.

During operation, then, when the trigger circuit is on the mark side the triode 110 is conducting and the triode 114 is non-conducting. All the code groups of the type printer this unit is arranged to receive, end in a stop character which is a mark character. Therefore, when keying stops, the trigger keyer control of the frequency shift keying unit is normally left on the mark side, i. e., tube 110 conducts. It would be possible, however, for a pulse of noise to trip the trigger to the space side, i. e., tube 114 conducts, and leave it there. In such an event tube 150 restores the circuit to mark side by drawing current through the resistor 117 connected to the triode 114 grid which results in a lowering of the potential on that grid and hence a lowering of the conduction of that triode 114 to the point where trigger action takes place and the tube 114 triggers to complete non-conduction and the triode 110 to conduction.

The first character of each printer code group is a start character which is always a space character. This start or space character appears as a negative pulse across the resistor 108, just referred to, and is of such amplitude that its action on the grid of tube 150 through the connecting condenser 152 renders tube 150 non-conducting for the duration of the space character. This leaves the trigger free to react to the less positive pulse fed to the triode 110 grid. This pulse on the grid of tube 110 causes it to trigger to the non-conducting or space condition and of course the triode 114 to conduction. Any mark character which follows, being of more positive polarity across the resistor 108, is partially rectified on the grid of tube 150 so that tube 150 is conducting on this mark character. Being conducting, it places a less positive pulse on the triode 114 grid which aids the more positive mark pulse on the triode 110 grid in triggering to mark condition. Therefore while keying is in progress, tube 150 aids in keying the trigger. When keying stops, ending as has been stated in a mark character appearing on

the grid of tube 150 is partially rectified at this grid as previously described, but the resulting negative charge on the condenser 152 soon leaks off, in the absence of keying, and leaves tube 150 fully conductive and ready to restore the trigger in the event noise upsets it.

The use of a cathode to ground resistance in conventional trigger tube circuits to get the negative grid potential is known. In our improved system the cathode resistance 111 has this and an additional function. The keyed wave at 102, and 108 may not be of rectangular wave form. The leading and trailing edges may slope as shown in Fig. 2. The resulting mark and space time intervals may then be unequal as illustrated in Figs. 3 and 4 unless the reversals take place at the proper time as set by tripping tube bias and signal pulse magnitude at which tripping takes place. The variable resistance 111 is a means for adjusting the point at which the tripping action takes place. In other words, adjustment of 111 varies the bias on the grid of 110 which is overcome by the potential at 108 to set the tripping action in motion. In practice the magnitude of signal pulse at which the trigger is tripped to the mark condition may not be equal to the signal potential at which the trigger trips to the space condition. For example, the trigger may trip to mark when the signal magnitude reaches a value represented at "a," Fig. 2, and trip back to space when the signal magnitude falls to a value represented at "b." In this case mark is longer than space, as shown in Fig. 3. When the tripping action takes place at "c" and "d," Fig. 2, space is longer than mark, as shown in Fig. 4. In practice, adjustment is such that mark and space are made equal.

What is claimed is:

1. In a signalling system in combination, a triggering circuit comprising a pair of electrode structures having electrodes including an anode, a grid and a cathode, impedances cross-coupling the grid and anode electrodes of said structures and coupling said electrodes to direct current potential sources such that when current starts to flow in one structure the bias on the grid of the other structure relative to its cathode is reduced to reduce current therein and vice versa, and current is tripped through one structure and cut off in the other structure and vice versa, a source of pulse energy of varying magnitude coupled to the grid of one structure to control the current through the structures, said pulse energy representing signals arranged to terminate in the same character so that a first one of said pair of structures is normally left in a conductive condition and the second structure is left in a non-conductive condition, and means for restoring said conditions in the event static or other disturbance leaves said first structure non-conductive and said second structure conductive, comprising a resistance between the grid of the second structure and its cathode, an additional tube having input electrodes which are normally biased so the additional tube is conductive and having output electrodes connected across said resistance, and means for applying said pulse energy to the input electrodes of said additional tube.

2. In combination, a circuit comprising two electrode structures each having an anode, a cathode and a control grid, a resistance coupling the anode of each structure to the grid of the other structure, additional resistances coupling the electrodes to a source of potential such that

when current starts to flow in a first structure the bias on the grid of the second structure relative to its cathode is reduced to reduce current therein and current is tripped through said first structure and cut off in the second structure and vice versa, a third resistance between the grid of said second structure and ground, a variable resistance between the cathode of said second structure and ground, a source of pulse energy of varying magnitude coupled to an electrode of one of said structures to control the current flow therethrough, said pulse energy representing signals which terminate in a manner to cut off current in said second structure, and means for restoring such terminal condition in the event static or other disturbance has altered the same including a third tube having output electrodes including an anode and a grounded cathode and having input electrodes including said grounded cathode coupled to said pulse energy source, means for applying a slightly positive biasing potential to said input electrodes, and a connection between the anode of said third tube and the control grid of said second structure.

3. In telegraphy apparatus, in combination, a circuit comprising two tubes each having electrodes including a cathode, an anode, and a grid; impedances cross-coupling the grid and anode electrodes of said tubes and coupling said electrodes to direct current potential sources such that when current starts to flow in a first tube the bias on the grid of the second tube relative to its cathode is reduced to reduce current therein, so that current is tripped through said first tube and cut off in said second tube, and vice versa; biasing circuits for the grids of both tubes including a resistor between the grid and cathode of said second tube; an output circuit coupled to one of said tubes; a source of pulse energy of varying magnitude coupled to the control grid of said first tube to control the current flow therethrough, said pulse energy having a wave shape representing signals which terminate in a manner to cut off current in said second tube; and means for restoring such terminal condition in the event static or other disturbance has altered the same, said means including a third tube having output electrodes and having input electrodes coupled to said source of pulse energy; means for applying a slightly positive biasing potential to the input electrodes of said third tube; output circuit connections for said third tube including in series its output electrodes, the impedance connected between the grid of said second tube and the anode of said first tube, and a source of direct current potential; and means connecting the output electrodes of said third tube in shunt to said resistor.

4. In combination, a triggering circuit comprising two tubes, each having an anode, a cathode, and a control grid; a resistance coupling the anode of each tube to the grid of the other tube; connections for applying charging potentials to the anodes of said tubes and biasing potentials to the grids of said tubes, such that when current starts to flow in one tube, the bias on the grid of the other tube is reduced to reduce current therein and current is tripped through said one tube and cut off in the other tube, and vice versa; a resistance between the grid of each of the tubes and ground; means for adjusting the bias on the grids of the tubes to vary the point at which tripping action takes place, including a variable resistance in the common connection between the cathodes of said tubes and ground; a source of

pulse energy of varying magnitude coupled to the control grid of a first one of said tubes to control the current flow therethrough, said pulse energy representing signals which terminate in a manner to cut off current in the second one of said tubes; and means for restoring such terminal condition in the event static or other disturbance has altered the same, including a third tube having output electrodes comprising an anode and a grounded cathode and having input electrodes including said grounded cathode coupled to said pulse energy source; means for applying a slightly positive biasing potential to the input electrodes of said third tube; a connection between the anode of said third tube and the control grid of said second tube; and an output circuit coupled to one of said first two tubes.

5. In telegraphy signalling apparatus, a circuit comprising two tubes, each having electrodes including a cathode, an anode, and a grid; connections cross-coupling the anodes and grids; connections for applying charging potentials to the anodes and bias to the grids, such that when current starts to flow in one tube the bias on the grid of the other tube is reduced to reduce current therein so that current is tripped through said one tube and cut off in the other tube, and vice versa; a first resistance in the coupling between the anode of one tube and the grid of the other tube; a second resistance between the grid of the other tube and ground; a source of pulse energy the magnitude of which varies relative to ground; means coupling said source to the control grid of said one tube to control the current therethrough; a common adjustable resistance between the cathodes of both said tubes and ground; a third tube having output electrodes and having input electrodes, including a control grid, coupled to said pulse energy source; means for applying a slightly positive biasing potential to said control grid of said third tube; and means connecting the output electrodes of said third tube in shunt to said second resistance.

6. In combination, a circuit comprising two tubes each having electrodes including a cath-

ode, an anode, and a grid; a resistance coupling the anode of each tube to the grid of the other tube; connections for applying charging potentials to the anodes of said tubes and biasing potentials to the grids of such tubes, such that when current starts to flow in one tube the bias on the grid of the other tube is reduced to reduce current therein, and current is tripped through said one tube and cut off in the other, and vice versa; a third resistance between the cathode and grid of said other tube; a third tube having input electrodes including a grid and also output electrodes; means for applying a slightly positive biasing potential to said input electrodes; means connecting the output electrodes of said third tube in shunt to said third resistance; a fourth tube having input electrodes including a cathode excited by pulse energy representing signals and having an output circuit including a resistance connected between its cathode and ground; means connecting said fourth tube to a source of energy for energizing the same; a coupling between the cathode of the fourth tube and the grid of the third tube and the grid of said one of said first two tubes; and an output circuit coupled to an output electrode of one of said first two tubes.
